UNITED STATES PATENT OFFICE

GEORGE REMNSIDER, OF BELLEVILLE, ILLINOIS

ROLL-HOLDING MECHANISM

Original application filed December 2, 1927, Serial No. 237,189. Divided and this application filed September 4, 1928. Serial No. 303,843.

My invention relates to a roll holding mechanism and in the form shown is specifically applicable to a tape delivering machine, such as shown and described in my application Serial No. 237,189 filed December 2, 1927, of which the present application is a division.

The object of my invention is to provide a roll holder for tape delivering or similar machine which is adaptable to various widths of tape and which will automatically center the roll in the machine.

In the accompanying drawings, which illustrate one form of mechanism made in accordance with my invention, Figure 1 is a side elevation on a reduced scale; Figure 2 is a section taken on the line 2-2 of Figure 3; and Figure 3 is a top plan view.

The frame of the machine comprises a right hand casting 5 and a left hand casting 6 terminating at the forward ends in circular gear casings 7 and 8, respectively, and provided with feet 9 upon which the machine is supported. Extending between the casings 7 and 8 are a pair of feed rolls 10 and 11 to which the tape passes from the roll 12 over a tape guide 13. A handle 14 actuates the rolls 10 and 11 by means of gearing disclosed in my application mentioned above but not here shown as it is not essential to the present invention.

The rear ends of the castings 5 and 6 are spaced apart by a central cross rod 15 which, together with a pair of cross rods 16, arranged one at the front and the other at the rear of the rod 15, forms the support for the roll holding mechanism. Slidingly mounted on the cross bars are a pair of roll frames 17 each provided on its inner face with a boss 18 adapted to enter the hole in the center block on which the roll is wound. Each of the frames 17 is provided with a central lug 19 forming a bearing for the rod 15 and with an elongated bearing 20 engaging with one of the rods 16. Formed on each of the bearings 20 is an extension 22 in which is pivotally mounted a downwardly projecting stud 23. 24 is the operating lever rigidly held in a stud 25 and sliding in the studs 23. Carried by the stud 25 is a short rock shaft 26

passing down through the bar 15 to form a pivot for the stud and operating lever and having secured to its lower end an arm 27. Pivoted to the end of the arm by means of a stud 28 is a rod 29 surrounded by a coil spring 30 and extending through the side frame 5. The tension of the spring 30 tends to move the arm 27 toward the left hand frame 6 and thus force the roll frames 17 toward each other.

To insert a roll of tape in the device the rear end of the operating lever 24 is forced toward the right hand frame 5 against the pressure of the spring 30 until the roll frames 17 are separated a sufficient distance to allow the roll to enter between the bosses 18. The hole in the center block is brought into alignment with the bosses and the operating lever released to allow the spring 30 to force the frames toward each other and clamp the roll in position. As the frames are in all positions at equal distances from the center line of the machine the device not only automatically adjusts itself to the width of the tape but also accurately centers the roll of tape in the machine. The pressure of the frames on the ends of the roll also acts as a brake to prevent the over rotation of the roll as the tape is unwound.

Having fully described my invention, what I claim as new and desire to secure by Letters Patent of the United States is:

1. In a device of the class described, the combination with a pair of laterally movable frames, of a pivoted actuating lever for said frames, said lever having sliding connections with one of said frames at one side of its pivot and with the other frame at the other side of said pivot.

2. In a device of the class described, the combination with a pair of laterally movable frames, of a pivoted actuating lever for said frames, said lever having sliding connections with one of said frames at one side of its pivot and with the other frame at the other side of said pivot, and a spring tending to move said frames toward each other.

3. In a device of the class described, the combination with a pair of laterally movable frames, of an operating lever provided with a

pivot, a sliding connection carried by one of said frames and engaging with the lever at one side of the pivot, and a second sliding connection carried by the other frame and engaging with the lever at an equal distance 5 at the other side of the pivot.

4. In a device of the class described, the combination with a central supporting bar, of two lateral supporting bars, one arranged 10 at each side of the central bar, a roll carrying frame having a sliding bearing on said central supporting bar and on one of said lateral supporting bars, a second roll carrying frame having a sliding bearing on the central supporting bar and on the other lateral supporting bar, an actuating lever pivoted to said central supporting bar and having sliding connections with the bearings on both lateral supporting bars, and a spring operating on 15 said actuating rod to move said frames toward each other.

5. In a device of the class described, the combination with a supporting bar, of a pair of frames slidably mounted on said bar, a 20 swivel block carried by each of said frames, and a pivotal operating lever having sliding engagement with said swivel blocks.

6. In a device of the class described, the combination with a supporting bar, of a pair 25 of frames slidably mounted on said bar, one of said frames being provided with an inwardly extending projection at one side of said bar and the other frame being provided with a similar projection on the other side of 30 the bar, a swivel block carried by each of said projections, and a pivotal operating lever having sliding engagement with said swivel blocks.

7. In a device of the class described, the combination with a central supporting bar, 35 of two lateral supporting bars, one arranged at each side of the central bar, a pair of frames slidably mounted on said central bar, one of said frames being provided with an inwardly projecting bearing sliding one of 40 said lateral bars and the other being provided with a similar bearing sliding on the other of said lateral bars, a swivel block carried by each of said bearings, and a pivotal operating lever having sliding engagement with said 45 swivel blocks.

In testimony whereof, I hereunto affix my signature, this 31st day of August, 1928.

GEORGE REMNSNIER.
